UNITED STATES PATENT OFFICE

91,467

DESIGN FOR A WATER CLOSET

Charles F. Mink, Larchmont, N. Y.

Application June 24, 1933. Serial No. 48,520

Term of patent 14 years

To all whom it may concern:

Be it known that I, CHARLES F. MINK, a citizen of the United States, residing at Larchmont, in the county of Westchester and State of New York, have invented a new, original, and ornamental Design for Water Closet, of which the following is a specification, reference being had to the accompanying drawings, forming part thereof, and in which:

Figure 1 is a front view of a water closet fixture;

Figure 2 is plan or top view thereof;

Figure 3 is a side elevation of same.

The essential feature of my design is the inclusion of an ornamental element which forms a part of the design and which conveys the impression of a supporting member for the bowl or principal member of the plumbing fixture.

I claim:

The ornamental design for a water closet, as shown and described.

CHARLES F. MINK.
